RAILWAY DRAFT RIGGING

John F. O'Connor, Chicago, Ill., assignor to W. H. Miner, Inc., Chicago, Ill., a corporation of Delaware

Application February 9, 1931. Serial No. 514,457

3 Claims. (Cl. 213—51)

This invention relates to improvements in railway draft riggings.

One object of the invention is to provide a railway draft rigging having longer travel in buff than in draft to provide for correspondingly greater shock absorbing capacity in the former action, including a friction shock absorbing mechanism having a compression stroke of sufficient length to take care of the longer travel in buff, wherein follower-acting means is employed cooperating with the end of the friction shell of the shock absorbing mechanism to limit the compression in buff and stop means is provided, also cooperating with said follower means for restricting the compression stroke in draft of the friction shock absorbing mechanism to less than the buffing stroke thereof.

Another object of the invention is to provide in a draft rigging of the character described in the preceding paragraph stop means for holding the friction shell of the shock absorbing mechanism against forward movement in a draft action, and during said action restricting the movement of the follower which cooperates with the friction means to less than the full compression stroke of said friction mechanism.

A still further object of the invention is to provide a combined stop means of the character specified in the preceding paragraph, which also acts as a supporting means for the friction shock absorbing mechanism.

A further object of the invention is to provide a railway draft rigging having a longer stroke in buff than in draft, including a coupler, a yoke connected to the coupler, a friction shock absorbing mechanism including a friction shell and cooperating friction elements, disposed within the yoke, and combined stop means for holding the shell against forward movement in draft, and restricting the compression stroke in draft to less than the full compression stroke of the friction shock absorbing mechanism, wherein the yoke is provided with rear follower means having a boss thereon engaging the friction elements and adapted to telescope within the friction shell, the compression stroke in draft being limited by engagement of said rear follower means with said stop means and the longer stroke in buff being provided by rearward movement of the shell through engagement by the inwardly moving coupler shank and telescoping of the boss within the shell, the stroke in buff being limited by engagement of the rear end of the shell with the rear follower means.

Other objects of the invention will more clearly

appear from the description and claims herein-after following.

In the drawing, forming a part of this specification, Figure 1 is a horizontal, longitudinal, sectional view of a portion of the underframe structure of a railway car, at one end of the same, illustrating my improvements in connection therewith. Figure 2 is a vertical, longitudinal, sectional view, corresponding substantially to the line 2—2 of Figure 1. And Figure 3 is a transverse, vertical, sectional view corresponding to the line 3—3 of Figure 2, said view being broken in order to accommodate the same to the sheet of the drawing.

In said drawing, 10—10 indicate spaced channel shaped center or draft sills of a railway car 70 underframe, having the usual striking casting 11 fixed to the outer ends thereof, the striking casting carrying the usual carry iron member 12 having a wear plate thereon, which cooperates with the shank of the coupler in the usual manner. The rear stop member of the railway draft rigging is indicated by 13 and is of that type which forms a combined filler and stop member, being located between the sills at the body bolster of the car. Portions of the body bolster are indicated by 14—14. The striking casting 11 has rearwardly extending side portions 15—15, which are provided with alined coupler key guide openings 16—16, said members forming cheek plates and being seated in the usual openings provided 85 at the forward ends of the webs of the sills 10—10. The coupler, a portion of the head and the shank of which only are shown, is indicated by 17 and has the usual coupler key 18 associated therewith, the key extending through a transverse 90 opening provided in the shank.

In carrying out my invention, I provide broadly a yoke member A; a front follower B; a shock absorbing mechanism C; a top stop plate D; and a pair of combined supporting and bottom stop plates E and F.

The yoke member A is of the horizontal type and has spaced side arms 19—19, connected at their inner ends by a vertical, plate-like section 20, which forms the rear follower of the railway draft rigging and cooperates with the stop casting 13. At the forward ends, the side members are provided with alined coupler key-receiving slots 21—21, through which the coupler key 18 extends. As will be evident, the yoke 100 A is thus connected to the shank of the coupler for outward movement thereof in draft, and the coupler is movable rearwardly with respect to the yoke in buff, this movement being permitted by the length of the slots 21—21. The plate-like 110

rear follower section 20 of the yoke has a forwardly extending central boss 22 thereon which cooperates with the friction shock absorbing mechanism C, in a manner hereinafter pointed out.

The shock absorbing mechanism C is of the friction type, comprising a casing 23 open at the rear end and having a friction shell section of well known form provided at said rear end portion, with which the usual friction means comprising friction shoes 24—24 and cooperating wedge member 25 coacts. As is well understood, inward movement of the friction means with respect to the shell is opposed by the usual spring member which resists movement of the shoes 24—24. The wedge member 25 bears directly on the boss 22 of the rear follower means 20 and the boss 22, as clearly shown in Figures 1 and 2, is of such a size that it telescopes within the open end of the shell, thereby permitting relative movement of the shell and follower 20 in buff to the full extent of the compression stroke of the friction shock absorbing mechanism, said movement being limited by engagement of the open end of the shell with the front face of the follower member 20.

The front follower member B is in the form of a relatively heavy, rectangular plate and is interposed between the butt end of the coupler shank and the forward or closed end of the casing 23 of the friction shock absorbing mechanism.

The top stop plate D has a main body portion 26 provided with downturned side flanges 27—27, which are secured to the inner faces of the vertical webs of the sills 10—10. The flanges may be secured by any suitable means, rivets being herein shown extending through said flanges and the webs of the sills. At the forward end, the plate D is provided with a downwardly projecting, relatively thick flange portion 28, extending transversely between the sills 10—10 and forming an upper front stop member cooperating with the front follower B. The rear end face of the plate D forms stop means cooperating with the rear follower member 20, as hereinafter pointed out.

The combined stop and supporting plates E and F are disposed adjacent the front and rear ends of the mechanism, as clearly shown in Figures 1 and 2. The plate E extends transversely between the sills and is relatively short, as clearly shown in Figure 2. At the forward end, the plate E has an upstanding, relatively heavy flange 29 corresponding to the flange 28 of the plate D and forming a lower front stop shoulder cooperating with the follower B. The main body portion of the plate E is thickened, as clearly shown in Figures 2 and 3, and has a transverse key slot 30 therethrough for a purpose hereinafter pointed out. The stop plate F is also disposed between the sills 10—10 and has a thickened main body portion provided with a transverse key receiving slot, similar to the slot 30, described in connection with the plate E, said slot being also indicated by 30. The rear end edge of the plate F is in vertical alinement with the rear end edge of the plate D and said end edge face of the plate F forms a lower stop member in alinement with the stop member formed by the rear end face of the plate D and cooperating with the follower member 20. Both of the plates E and F are provided with upstanding side flanges 31—31, which engage the lower edges of the side arms 19—19 of the yoke, thereby supporting the yoke for sliding movement. The main body portions of the plates directly support the

friction shell 23 of the shock absorbing mechanism, and the front plate E also supports the front follower B for sliding movement. The plates E and F are fixed to the draft sills and supported by keys 32—32, extending through the key openings 30—30 of the plates E and F, respectively. The outer ends of the keys 32—32 are supported by angle plates 33—33 fixed to the draft sills and having openings therethrough accomodating the corresponding ends of the keys. As shown in Figure 3, the angle plates 33—33 are riveted and bolted to the bottom flanges of the sills 10—10, the bolts extending through the same, the keys and spacing plates 34—34 interposed between the bottom flanges of the sills and the heads of the bolts, the bolts serving to hold the keys against removal.

The normal position of the parts is that shown in Figures 1 and 2 of the drawing, and as will be seen upon reference to these figures the inner or rear end of the friction shell is spaced some distance forwardly of the stop faces formed by the rear end edges of the plates D and F. Further, the follower 20, which is formed integral with the yoke, is of such a height that the top and bottom portions thereof engage the rear end edges of the plates D and F, during a draft action, to restrict the forward movement of the follower 20 to less than the full compression stroke of the friction shock absorbing mechanism. The space between the flanges 28 and 29 of the plates D and E is such as to accommodate the coupler shank freely for movement lengthwise of the mechanism, thereby permitting compression of the friction shock absorbing mechanism to its full extent, the compression stroke of the latter being limited by engagement of the rear end of the shell 23 with the front face of the rear follower 20.

As will be evident, the friction shock absorbing mechanism and other parts of the railway draft rigging may be readily applied and removed, these operations being greatly facilitated by the detachable bottom plates E and F. As will be obvious, the entire mechanism may be placed in operative position between the sills and the plates E and F are then applied and secured by the keys 32—32. In detaching the parts of the railway draft rigging, it is merely necessary to remove the plates E and F by detaching the keys thereof.

The operation of my improved railway draft rigging is as follows: During a draft action, the coupler is pulled outwardly, thereby pulling the yoke A forwardly therewith and compressing the friction shock absorbing mechanism C against the front follower B, which is held stationary by engagement with the front stop members 28 and 29. The compression of the mechanism will continue until movement of the coupler and yoke is limited by engagement of the rear follower member 20 with the inner ends of the plates D and F. As will be clear, movement of the follower 20 is restricted to less than the full compression stroke of the friction shock absorbing mechanism. In a buffing action, the coupler is forced inwardly, thereby forcing the front follower B rearwardly and carrying the friction shell or casing 23 therewith, and compressing the friction shock absorbing mechanism against the rear follower 20, which is held stationary by engagement with the stop means 13 during the compression of the friction shock absorbing mechanism in buff. The boss 22 of the follower 20 will enter the open end of the friction shell, relative movement of

the shell 23 and the follower 20 being finally limited by engagement of the rear end of the shell with the front face of said follower. As will be clear, this stroke is much in excess of the draft stroke hereinbefore described.

5 I have herein shown and described what I now consider the preferred manner of carrying out my invention, but the same is merely illustrative and I contemplate all changes and modifications that come within the scope of the claims appended hereto.

I claim:

1. In a railway draft rigging, the combination with spaced draft sills; of rear stop means; a coupler; a friction shock absorbing mechanism including a casing open at one end and having a friction shell section at said open end, and friction elements cooperating with said shell; front follower means interposed between the friction casing and the coupler butt; front stop means for limiting outward movement of said front follower; a rear follower actuated by the coupler in draft, said rear follower having a forwardly projecting boss thereon adapted to telescope within the open end of the friction shell, whereby said boss enters the shell during a buffing action of the mechanism and the buffing stroke is limited by engagement between said rear follower and the open end of the shell; and stop means engageable by said rear follower for restricting forward movement of said rear follower in draft to less than the buffing stroke of said friction shock absorbing mechanism.

2. In a railway draft rigging, the combination

35

with spaced draft sills; of a shock absorbing mechanism between said sills; front and rear followers cooperating with said shock absorbing mechanism; a rear stop member between said sills for limiting rearward movement of the rear follower; front stop means for limiting forward movement of the front follower; additional stop means for limiting forward movement of said rear follower; and a supporting plate for the shock absorbing mechanism, said plate being disposed forwardly of said rear follower, the rear edge of said supporting plate providing an abutment shoulder forming a part of said additional stop means for the rear follower.

3. In a railway draft rigging, the combination with spaced draft sills; of a rear stop member between said sills; a coupler; a shock absorbing mechanism; rear follower means actuated by said coupler in draft; and combined stop and supporting means, said combined means supporting the shock absorbing mechanism and having front and rear stop shoulders, said combined means including a supporting shelf having one of said stop shoulders formed thereon for holding the shock absorbing mechanism against forward movement in draft, said combined means also including a second supporting shelf forwardly of said rear follower means, the rear edge of said last named shelf forming another of said stop shoulders and being engageable by said rear follower means for restricting forward movement of said rear follower means.
